Primary Examiner — Kelley Donnelly*(74) Attorney, Agent, or Firm* — Holtz, Holtz, Goodman & Chick, PC(57) **CLAIM**

An ornamental design for a multi-position organizer, as shown and described.

DESCRIPTION

FIG. 1 is a front, top perspective view of a multi-position organizer showing my new design;

FIG. 2 is a front elevational view thereof;

FIG. 3 is a rear elevational view thereof;

FIG. 4 is a right side view thereof;

FIG. 5 is a left side view thereof;

FIG. 6 is a top plan view thereof;

FIG. 7 is a bottom plan view thereof;

FIG. 8 is a perspective view thereof shown in a different orientation;

FIG. 9 is a perspective view thereof shown in still another orientation; and,

FIG. 10 is a perspective view thereof shown in still another orientation of use.

The broken line portions of the drawings are for illustrative purposes only, and form no part of the claimed design.
